UNITED STATES PATENT OFFICE

FRED D. WILSON, OF HARVEY, ILLINOIS, ASSIGNOR TO AUSTIN MANUFACTURING CO., OF CHICAGO, ILLINOIS, A CORPORATION OF ILLINOIS

BANK SLOPER

Application filed October 28, 1926. Serial No. 144,785.

This invention relates to road graders and more particularly so-called bank sloping machines, in which the main or road scraping blade of the machine is equipped at one end with a vertically, angularly adjustable bank sloping blade capable of cutting ditch walls or other surfaces at an angle to the cutting surface of the main blade. The primary object of the invention is to provide such a device in which the angle of the sloper blade may be changed not only from the operator's station at the rear of the machine but while the machine is either moving or standing still.

The invention consists in mechanism capable of carrying out the foregoing and other objects; which can be easily and comparatively cheaply made; which is highly efficient and otherwise satisfactory in operation and is not readily liable to get out of order.

More particularly, the invention consists in detailed mechanism by which the sloper blade can be positioned with reference to a given position of the main blade to cut an upwardly inclined surface or a downwardly inclined surface, and more particularly in mechanism by which each adjustment of the main blade angularly in a vertical plane or angularly in a horizontal plane or vertically or transversely of the machine may be used to effect to a greater or less extent desired adjustment of the bank sloper blade.

The invention further consists in numerous features and details of construction which will be hereafter more fully set forth in the specification and claims.

Referring to the drawings in which like numerals designate the same parts throughout the several views:

Figure 1 is a side elevation of the machine illustrating this invention in its preferred form, the bank sloper blade being in a position to cut a vertically inclined earth surface.

Figure 2 is a plan, detail view on the line 2-2 of Figure 1.

Figure 3 is a plan view of the mechanism of Fig. 1.

Figure 4 is a front view of the machine shown in Figures 1 and 3 with the blade op-

erating to bank slope the upwardly inclined wall of a ditch.

Figure 5 is a changed position view of the mechanism of Figure 4 showing the bank sloper blade adjusted to cut a downwardly inclined surface, specifically the upper end of the surface on which the right hand wheel of Figure 4 rests.

The mechanism of this invention is applied to a conventional form of grader including rear wheels 10, front wheels 12, connecting arched frame 14, equipped at the rear with an operator's station or platform 16, the whole drawn over the ground by suitable power not shown attached to a drawn tongue 18.

The wheels 10 are conventionally, laterally shiftable cross-wise of the machine as shown in dotted lines 20, Figures 4 and 5, and each wheel 10 and 12 is conventionally, laterally tilttable in a vertical plane as clearly shown in Figures 4 and 5.

Conventionally pivoted at 22 on the front axle mechanism 24 of the machine and below the frame 14 is a horizontally swinging frame 26-28-30 whose rear end is conventionally attached through the link mechanism 32 to a horizontally disposed chain 34 passing over sprocket wheels 36 at opposite sides of the machine, one of which is conventionally operable through a vertically disposed shaft 38 and hand wheel 40 located conveniently to the operator's station 16. By properly manipulating handwheel 40, the operator can in conventional manner move chain 34 crosswise of the machine to swing the frame 26-28-30 about pivot 22 crosswise of the machine in a horizontal plane and thereby laterally vary the position of the main road working blade 42.

This blade 42 is rigidly secured through depending bracket arms 44 to a horizontally rotatable, conventional wheel 46 journaled on a part 48 of frame 26-28-30. This wheel 46 is provided on its rear circumference with a segmental worm gear 50 engaged by a conventional worm not shown, located on shaft 52 back of bevel gear 54 appearing in Figure 1. This latter gear meshes with another bevel gear 56 driven through a uni-

versal joint 58 by a shaft 60 equipped at its rear end with a hand wheel 62 within ready reach of the operator's station 16. The operator at said station 16 can by manipulating wheel 62 in the proper direction operate the gearing mechanism described to rotate wheel 46 in either direction as desired to change the angular, horizontal position of main blade 42. The universal joint 58 permits this operation of the blade 42 in all horizontal, lateral positions of the frame 26-28-30.

On each side of frame 26-28-30 is a horizontal pin or shaft 64 to which is pivotally attached an upwardly extending connecting rod 66. The upper end of each of these rods is pivotally connected to an independent bell crank lever 68 pivotally supported at 70 on a suitable bracket 72 extending upwardly from the frame 14. The opposite arm of bell crank 68 is pivotally connected at 74 to a downwardly inclined rod or rack 76 having at its lower end a rack 78 traversed by a pinion 80 operatable through gearing 82-84 by a hand wheel 86. As clearly shown in the drawings, there is one such hand wheel at each side of the machine adjacent to the operator's station 16 and, obviously, by manipulating said hand wheel 86, the operator at the station can raise or lower a selected one or both of the sides of the frame 26-30, thereby raising or lowering as desired either end of the main blade 42. The pivotal connections 64 heretofore referred to are conventionally such as to permit this adjustment in all lateral positions of the frame 26-30.

The front wheels 12 and the axle 24 therefore are conventionally rotatable in a horizontal plane for steering the machine through a conventionally connected, laterally extending shaft 88 conventionally operable at the rear of the machine through manipulation of hand wheel 90 located at the operator's station.

Pivotedly connected to the forward end of the road-working blade 42 on a suitably positioned, horizontally disposed pivot bolt 92 is a vertically tiltable bank sloper blade 94 selectively movable at the will of the operator between the upwardly inclined position of Figure 4 and the downwardly inclined position of Figure 5. Pivotedly attached to this bank sloper blade 94 at a convenient point near its outer or free swinging end on a pivot bolt 96 is a generally horizontally disposed rod 98 extending in general parallel to main blade 42 transversely of the frame 14 of the machine. This rod 98 is pivotally connected at 100 to a depending lock on a cross-head 102, rigidly secured to a reciprocal non-rotatable shaft 104 carried on depending brackets 106 and 107 on the under side of frame 14. This shaft 104 is rendered non-

rotative while permitting reciprocation through the agency of a spline connection 108 with the bearings 110 on the lower end of bracket 106. Shaft 104 beyond cross-head 102 is provided with screw threads 112 traversed by the hub 114 of a bevel gear 116 located within a suitable housing 118 carried by bracket 107. Also in this housing and meshing with gear 116 is another beveled gear 120 on a short shaft 122 terminating in a universal joint 124. Connected to this universal joint 124 is an inclined shaft 126 extending to the rear of the machine and equipped at the operator's station 16 with a manually manipulatable crank handle 128. It is obvious that the operator can by turning crank handle 128 so move the gearing mechanism in housing 118 as to cause shaft 104 to travel horizontally cross-wise of the machine and thus pull or push, as the case may be, rod 98 to forcibly raise or lower the outer end of bank sloper blade 94, thereby changing its angular, vertical position.

In order to enable bank sloper blade 94 to withstand the strain upon its outer end occasioned by doing the work required of the mechanism of this invention, a multiplicity—in the particular case here illustrated two—chain hook holes 130 and 132 are provided adjacent to the outer end of the blade 94 each of these holes being selectively engageable by the hook 134 of a chain 136, detachably, adjustably connectable to the front portion of the grader mechanism.

In the particular case here illustrated, two brackets 138 and 140 are provided on the front frame of the machine. The lower bracket 138 extends, as shown in Figure 1, a substantial distance forward of bracket 140. Bracket 138 is provided with an end notch 142 and bracket 140 is provided with a corresponding end notch 144 in which the chain 136 may be lockingly inserted. By properly combining the chain 136 at its inner end with these brackets and at its outer ends with the holes 130 and 132 in the end of bank sloper blade 94, all desired conditions of chain support required by the blade to work as shown in Figure 4 or as shown in Figure 5 may be obtained.

There is sufficient play in the universal joint 124, the connection 100 and the connection 96 so that blade 94 may be adjusted as desired and described in all the adjusted positions heretofore described of main blade 42.

From the foregoing, it will be seen that assuming blade 42 is in fixed position, the operator can by manipulating handle 128 raise and lower the outer end of blade 94 to change the vertical, angular position of blade 94; that by detaching the outer end of rod 98 from the blade 94-96, and by properly adjusting the chain 136, the blade 130

94 may be swung to the downwardly inclined position of Figure 5.

It will further be seen that in all such adjusted positions of the outer end of blade 94, further adjustment of said blade 94 may be made by each separate previously described adjustment of blade 42, either angularly in a horizontal plane or angularly in a vertical plane or up and down without angular adjustment or laterally of the machine.

All these last described adjustments effected through the change in position of blade 42 can be made from the operator's station with the machine in motion. It is apparent that the operator has all possible desired adjustments of the blade under his control while the machine is in motion. The only adjustments in the entire machine which require manual manipulation when the machine is at rest are the adjustment of the chain 136 and the disconnection of rod 98 from blade 94 when changing the blade from the position of Figure 4 to that of Figure 5.

In the operation of the machine on the road, suggested by the drawings, the machine is first positioned as shown in Figure 4 wherein the blade 42 cuts the ditch surface 146 and the blade 94 cuts the ditch surface 148, the two blades 94 and 42 operating to deliver the severed dirt 150 into the position shown in Figure 5 on road surface 152. After the machine has completed the work just described, the machine is then sent along the road over surface 152 as illustrated in Figure 5 with the blade 94 lowered as shown in that figure to then scrape road surfaces 146 and 152 to thereby deliver the loose dirt off at the right hand side 154 of road surface 152.

In the complete operation of the device, the wheels 10 and 12 are, by conventional means not shown, tilted and wheels 10 are laterally shifted as the road conditions may require to properly perform the necessary work.

The chain 136 at the front of the machine, supporting the front end of the sloper blade is, of course, a tension device and it will be so referred to in some of the claims.

The sloper blade is, of course, broadly a supplemental blade and will be so referred to in some of the claims.

Having thus described my invention, what I claim as new and desire to secure by Letters Patent is:

1. In combination with a road grader having a main frame, supporting wheels and a road working blade, a supplemental blade pivoted to one end of the road working blade for movement in a vertical plane, an adjustable tension device connecting the blade and the main frame of the grader, the tension device being adjustable to permit the supplemental blade being selectively, angu-

larly disposed upwardly or downwardly from the end of the road working blade, and means selectively changing the point of connection of the tension device to the supplemental blade.

2. In a road grader, the combination with a main frame, supporting wheels therefor, and a road working blade mounted in said frame, of a supplemental blade pivotally connected to said road working blade, an adjusting unit consisting of two complementary threaded members, one of which is rotatable with respect to the other, an operating member connecting said supplemental blade and said adjusting unit, and means independent of said connecting member and rotatable with respect to said adjusting unit for actuating said unit, so that the position of said supplemental blade may be changed during travel of the grader.

3. In a road grader, the combination with a main frame, supporting wheels therefor, and a road working blade mounted in said frame, of a supplemental blade pivotally connected to said road working blade, a non-travelling rotatable adjusting member, a complementary adjusting member engaging said rotatable member, said last mentioned member being non-rotatable, but mounted to travel rectilinearly, a link connecting the travelling adjusting member with said supplemental blade, and means independent of said link and having rotative engagement with the rotatable adjusting member for actuating the same, so that the position of said supplemental blade may be changed during travel of the grader.

4. In a road grader, the combination with a main frame, supporting wheels therefor, and a road working blade mounted in said frame, of a supplemental blade pivotally connected to said road working blade, a rotatable nut mounted in the frame and held in a normally fixed location, a longitudinally movable threaded shaft engaging said nut, a link connecting said shaft with said supplemental blade, and means independent of said link for actuating said nut, so that the position of said supplemental blade may be changed during travel of the grader.

5. In a road grader, the combination with a main frame, supporting wheels therefor, and a road working blade mounted in said frame, of a supplemental blade pivotally connected to said road working blade, a bracket supported by said frame, a nut rotatably mounted in said bracket, a second bracket spaced from the first bracket, a rotatable shaft having one end mounted in the second bracket and its other end in engagement with said nut, a link connecting said shaft with said supplemental blade, and means for rotating said nut so that the position of the supplemental blade may be changed during travel of the grader.

6. In a road grader provided with a main frame and an angularly adjustable main blade, a supplemental bank-cutting blade pivotally connected to one end of the main
5 blade, adjustable tension means connected with the grader frame and also with the outer end of the supplemental cutting blade, a connecting member having one end connected with said supplemental cutting blade, adjusting means connected with the other end of said connecting member, and operating means independent of said connecting member and rotative with respect to said adjusting means, said operating means being controlled from the operator's station, so that the angular position of the supplemental cutting blade may be changed during travel
10 of the grader.
15

In witness whereof, I have hereunto subscribed my name.

FRED D. WILSON.
